(57) **CLAIM**

The ornamental design for a modular LED strip for a headlamp, as shown and described.

DESCRIPTION

FIG. 1 is an elevated isometric view of a modular LED strip for a headlamp showing the new design;

FIG. 2 is a front side view of the modular LED strip for a headlamp as shown in FIG. 1;

FIG. 3 is a back side view of the modular LED strip for a headlamp as shown in FIG. 1;

FIG. 4 is a left side view of the modular LED strip for a headlamp as shown in FIG. 1;

FIG. 5 is a right side view of the modular LED strip for a headlamp as shown in FIG. 1;

FIG. 6 is a top view of the modular LED strip for a headlamp as shown in FIG. 1;

FIG. 7 is a bottom view of the modular LED strip for a headlamp as shown in FIG. 1; and,

FIG. 8 is an environmental view of the modular LED strip for a headlamp as shown in FIG. 1.

The broken lines shown in the drawings depict portions of the modular LED strip for a headlamp that form no part of the claimed design. The additional broken lines shown in FIG. 8 depict environment only and form no part thereof.
